EAVES FORMING MEMBER

Carl Henning, Kansas City, Mo., assignor to
Andrew A. Kramer, Kansas City, Mo.

Original application October 27, 1938, Serial No.
237,249. Divided and this application January
28, 1939, Serial No. 253,373

8 Claims. (Cl. 189—1)

My invention relates to metal building structures, and more particularly to an eaves-forming member used in wall construction for metal houses, this being a division of my application 5 for patent on Wall construction for metal houses, Serial No. 237,249, filed October 27, 1938.

It is a purpose of my invention to provide a wall for metal buildings, which comprises wall panels and columns that alternate with each 10 other and all of which are made of sheet metal, with eaves-forming members which constitute locking members for elements making up the wall, so as to hold said columns and panels in interlocking relationship, said eaves-forming 15 members and said columns and panels being provided with means thereon that interlock, and with means for clamping the eaves-forming members to said columns and panels to hold the elements of the wall in firmly interlocked relationship.

It is a further purpose of my invention to provide eaves-forming members that act as means for connecting the wall forming elements and the roof of the building, and which constitute 25 means for supporting the roof of said building, as well as for supporting gutter members.

Other objects and advantages of my invention will appear as the description of the drawing proceeds. I desire to have it understood, however, that I do not intend to limit myself to the 30 particular details shown or described, except as defined in the claims.

In the drawing:

Fig. 1 is a vertical transverse sectional view 35 through my improved eaves-forming member for sheet metal buildings.

Fig. 2 is a fragmentary sectional view of the upper portion of a column constituting part of the wall of a sheet metal building and of my improved eaves-forming members, showing the same interlocked therewith.

Fig. 3 is a fragmentary vertical sectional view 40 through the upper portion of a wall panel member and my improved eaves-forming member, showing the same interlocked therewith, and

Fig. 4 is a vertical longitudinal sectional view 45 through a portion of the top part of the wall and the lower portion of my improved eaves-forming member.

Referring in detail to the drawing, my improved eaves-forming member comprises a lower transverse portion made up of a horizontal wall portion 10, forming a flange directed inwardly from the vertical wall 11, which forms one side 50 of a depending hollow rib, or channel, portion,

having a bottom transverse wall 12, which is provided with an opening 13 and from which the vertical wall portion 14, of the same height as the wall 11, extends to the transverse wall portion 15, said wall portion 15 being integral with 5 the vertical side wall 16 of the eaves-forming member, which is provided with a laterally outwardly offset upper end portion 17 connected with the vertically extending portion 16, by means of the horizontal ledge portion 18. The 10 side wall thus constitutes a lower vertical portion 16 and an upper vertical portion 17 offset therefrom and connected by the portion 18. From the upper edge of the portion 17 the inwardly and upwardly inclined roof supporting 15 portion 19 extends. The eaves-forming member thus constitutes a vertical wall portion with an offset therein, a bottom transverse wall portion having a depending hollow rib, or channel formation, thereon, and a top wall portion that 20 is inclined upwardly from the vertical side wall portion.

A gutter member 20 of any desired configuration provided with straps 21 for bracing the same, and having an inner wall 22 engaging 25 face to face with the vertical wall 16, is provided on the eaves-forming member whenever desired, being, preferably, welded to the wall portion 16. The inclined top wall 19 supports any suitable roofing members 23, which are secured thereto by suitable fastening elements, such as the bolts 24 and nuts 25. It will be noted that the upwardly and inwardly inclined member 19 extends inwardly from the side wall 16 substantially the same distance as the flange 30 portion 10 of the bottom wall of the eaves-forming member.

The hollow rib formation on the bottom wall of the eaves-forming member is provided for interlockingly engaging with columns and wall 40 panel members. While the columns may be varied somewhat in contour and construction, and while only one column is illustrated in the drawing, it is to be understood that the eaves-forming member is interlocked with intermediate and 45 corner columns, which may vary somewhat in details of construction. However, all said columns have a box-like body portion having the vertical walls 26 and 27 and a top wall having the transverse portion 28, which is depressed below the top edges of the walls 27 and at least one of the walls 26, in the case of a corner column, and the opposite walls 26 in an intermediate column, are notched, or cut out, so as to receive a hollow rib formation made up of the 50 55

portions 11, 12 and 14 of the eaves-forming member, so as to snugly fit therein, the wall 12 engaging face to face with the transverse wall 28, said wall 28 being provided with a substantially 5 U-shaped keeper member 29, extending through the opening 13, with which a wedge 30 cooperates to clamp the hollow rib portion within the channel thus formed in the column. In the form of the invention shown in Fig. 2, the top 10 wall of the column is provided with an upper transverse portion 31 at each side of the depressed portion 28, connected therewith by means of the vertical wall portions 32, thus forming a channel in the top wall of the column corresponding 15 to the hollow rib on the eaves-forming member and receiving said hollow rib snugly. It will be noted that the outer wall of the column comprises a member 27 and a member 27' in face to face engagement and that the 20 wall portion 16 aligns with the outer wall member 27' of the column, and that the wall portion 15 of the eaves-forming member engages with one of the wall portions 31 and the flange 10 with the other wall portion 31.

25 Said eaves-forming member similarly cooperates with wall panel members having wide grooves receiving the hollow rib portions in the top walls thereof. Such a wall panel is shown in Fig. 3, said wall panel having an outer wall 33, to which the upstanding flange 34 on the channel, or groove forming member, having the bottom wall 35, is mounted, said channel, or groove, being completed by the vertical wall portion 36 forming part of a groove for receiving 30 an insulating board member 37 forming part of said wall panel. A U-shaped retaining, or keeper, member 29 is provided on the transverse bottom wall 35 of the channel, or groove, formed in the top of the wall panel, which is identical 35 with the member 29 shown in Fig. 2, and with which a wedge 30 cooperates in the same manner as previously described, the wall 12 on the eaves-forming member engaging face to face with the bottom wall 35 of the groove and the wall portions 40 14 and 11 being in face to face engagement with the vertical wall portions 34 and 36 of said groove. The transverse inwardly extending flange portion 10 engages the top transverse wall portion 38 on the wall panel member, 45 while the wall portion 15 on said eaves-forming member projects beyond the outer face of the vertical outer wall 33 of the wall panel member, as will be obvious from Fig. 2.

In my improved metal building, the transverse 50 end wall portions 39 of the wall panel members are spaced slightly from the walls 26 of the columns, as will be evident from Fig. 4, and the eaves-forming member, which also constitutes a top connecting member for the elements of the 55 wall, bridges the gap between the column members and the wall panel members, as will be evident from Fig. 4.

It will be obvious from Figs. 2, 3 and 4 that the eaves-forming member constitutes means for firmly clamping the wall panel and column members to each other through the keeper members 29 and wedges 30, holding the same in fixed position relative to each other both in a transverse and longitudinal direction with respect 60 to the wall in which said eaves-forming members, wall panels and columns are used.

What I claim is:

1. In metal building structure, the combination with sheet metal wall panel and column members having aligning channels in the top 75

walls thereof having wall portions depressed below the top edges of said panel and column members to provide longitudinal bottom walls for said channels, of a top connecting member having a depending hollow longitudinal rib 5 thereon fitting in said channels with a portion of said rib in face to face engagement with said bottom wall and means for clamping said connecting member to said panel and column members in interfitting relation therewith comprising 10 securing elements on said panel members.

2. In metal building structure, the combination with sheet metal wall panel and column members having aligning channels in the top 15 walls thereof having wall portions depressed below the top edges of said panel and column members to provide longitudinal bottom walls for said channels, of a top connecting member having a depending hollow longitudinal rib thereon fitting in said channels with a portion of 20 said rib in face to face engagement with said bottom wall and means for clamping said connecting member to said panel and column members in interfitting relation therewith comprising 25 securing elements on said panel members, said connecting member having an eaves-forming portion extending laterally and upwardly from said hollow rib.

3. In metal building structure, the combination with a wall comprising sheet metal wall 30 panel and column members having aligning channels in the top walls thereof extending longitudinally of said wall, said channels having bottom walls, of a top connecting member having a depending hollow longitudinal rib thereon 35 fitting in said channels with a portion of said rib engaging the bottom walls of said channels, and means for clamping said connecting member to said panel and column members in interfitting relation therewith comprising securing 40 elements on said panel members, said connecting member having an eaves-forming portion extending laterally and upwardly from said hollow rib and terminating in a roof supporting portion. 45

4. In metal building structure, the combination with a wall comprising sheet metal wall panel and column members having aligning channels in the top 50 walls thereof extending longitudinally of said wall, said channels having bottom walls, of a top connecting member having a depending hollow longitudinal rib thereon fitting in said channels with a portion of said rib engaging the bottom walls of said channels, and means for clamping said connecting member to 55 said panel and column members in interfitting relation therewith comprising securing elements on both said panel and column members, said connecting member having an upstanding wall at one side thereof comprising vertically extending 60 portions connected by a horizontal portion to form an offset in said upstanding wall.

5. In metal building structure, the combination with sheet metal wall panel and column members having aligning channels in the top 65 walls thereof, of a top connecting member having a depending hollow longitudinal rib thereon fitting in said channels and means for clamping said connecting member to said panel and column members in interfitting relation there- 70 with comprising securing elements on both said panel and column members, said connecting member having an upstanding wall at one side thereof comprising vertically extending portions connected by a horizontal portion to form an 75

offset in said upstanding wall, and an upwardly and inwardly inclined roof supporting portion extending from said upstanding wall.

6. In metal building structure, the combination with sheet metal wall panel and column members having aligning channels in the top walls thereof, of a top connecting member having a depending hollow longitudinal rib thereon fitting in said channels and means for clamping said connecting member to said panel and column members in interfitting relation therewith comprising securing elements on both said panel and column members, said connecting member having an eaves-forming portion extending laterally and upwardly from said hollow rib, and a gutter carried by said eaves-forming member.

7. In metal building structure, the combination with a wall comprising sheet metal wall panel and column members having aligning channels in the top walls thereof extending longitudinally of said wall, said channels having

bottom walls, of a top connecting member having a depending hollow longitudinal rib thereon fitting in said channels with a portion of said rib engaging the bottom walls of said channels, keeper members projecting upwardly from said bottom walls of said channels of both said columns and panel members, said rib having openings through which said keeper members extend, and wedges engaging said keeper members and the top face of said hollow rib to clamp 10 said top connecting member to both said panel and column members.

8. In a metal building structure, an eaves-forming member comprising a transverse portion having a depending longitudinally extending hollow rib thereon, an upstanding portion at one side of said transverse portion having a lateral offset therein, and a portion extending upwardly and inwardly at an oblique angle from said upstanding portion.

CARL HENNING.
